IGNITION SYSTEM.

1,167,483.

Specification of Letters Patent. Patented Jan. 11, 1916.

Application filed April 18, 1914. Serial No. 831,445.

To all whom it may concern:

Be it known that I, BURNS DICK, a subject of the King of England, residing at the city of St. Louis, State of Missouri, United States of America, have invented a certain new and useful Ignition System, of which the following is such a full, clear, and exact description as will enable any one skilled in the art to which it appertains to make and use the same, reference being had to the accompanying drawings, forming part of this specification.

My invention relates to an ignition system suitable for internal combustion engines.

One of my objects is to produce at will either a single spark or vibrator sparks, while reducing the minimum necessary advance of the single spark over the first vibrator spark to a very small angle.

Other advantages of my invention will appear from the detailed description and will be pointed out in the appended claims.

My invention is particularly applicable to an ignition system adapted to be operated from a storage battery or from a generator driven from the engine and designed to charge said battery after a certain engine speed has been exceeded. It is usual to provide an automatic battery switch between a storage battery and the dynamo adapted to charge same. In one form of my system, I make use of this automatic battery switch to change from vibrator to single sparks or vice versa.

Referring to the accompanying drawing, which illustrates one embodiment of my invention, the storage battery 7 is permanently connected to one of the main brushes 10 of the generator 9 driven by the explosion engine. The other main brush 13 of this generator can be connected to the other terminal of the storage battery by means of the automatic battery switch. The exciting winding 12 of the generator is connected between the main brush 10 and an auxiliary brush 11 displaced from the main brushes. The automatic battery switch comprises a movable armature 17 pivoted at 18, and normally under the control of spring 19, but is also under the influence of a magnet 14 energized by the shunt coil 15 connected across the main brushes of the dynamo, and a series coil 16 connected between the stationary contact 23 of the automatic switch and the main brush 13 of the dynamo. The

armature 17 of this switch carries two contacts 21, 22. The contact 21 rests on the stationary contact 20 as long as the spring 19 is in control of the armature 17. The contact 22 rests on the stationary contact 23 when the electromagnet of the automatic battery switch overpowers the spring 19 and attracts the armature 17.

The secondary ignition circuit comprises the secondary winding 4 of the spark coil 65 and one or more spark gaps such as 5, 6. A distributor of known construction is usually interposed between the spark gaps and the primary spark coil, but is not illustrated in the figure since it does not form a part of this invention. The spark coil is provided with a core 2.

The primary ignition circuit has two branches; one adapted to produce vibrator sparks and comprising the storage battery 7, 75 the primary 3 of the spark coil, the movable arm 40 of the circuit breaker pivoted at 41, the cam 39 co-operating therewith mechanically and electrically, and the vibrator 34. The cam 39 is either geared to the engine 80 shaft or directly connected thereto. This vibrator circuit is closed when the automatic battery switch is open. The other branch comprises the storage battery, the primary of the spark coil, the circuit breaker contacts 42, 43, and is closed when the automatic battery switch is closed. This single spark circuit can also be energized directly from the generator 9, for the latter is permanently in circuit with the primary of the 85 spark coil and the circuit breaker contacts 42, 43.

The ignition switch 31 has three positions. In the position 47 shown in the figure, it connects the storage battery 7 to the vibrator 95 circuit and closes the single spark circuit at the points 26, 27. In its position 48, it interrupts the single spark circuit and also disconnects the vibrator circuit from the battery. In its position 49, it connects the dry 100 cells 8 (provided for use instead of the storage battery, should the latter be temporarily out of condition,) in circuit with the primary of the spark coil and the circuit breaker contacts 42, 43, by bridging the 105 points 27 and 28 by means of the movable contact 29.

When the ignition switch is in the position shown in the figure, and the engine and, therefore, the dynamo 9 and the cam 110

39 are at rest and in the position shown, then the spring 19 will be in control of the armature 17 of the automatic battery switch and the vibrator circuit may be traced from 5 the negative pole of the battery through the spark coil to the breaker arm 40, to the cam 39 and the stationary contact 37 of the vibrator, the contact 36 attached to the spring-mounted armature 34 thereof pivot- 10 ed at 35, through the energizing coil 33 of said vibrator, the contacts 25, 30 and 24 of the ignition switch, the stationary contact 20 coöperating with the contact 21 of the automatic battery switch, and through the 15 armature of the latter back to the positive pole of the storage battery. As long as the cam 39 is in electrical contact with the breaker arm 40, the vibrator will be in operation, and vibrator sparks will be pro- 20 duced between points 5 and 6. During the whole of this period, the single spark circuit will be interrupted at the points 42 and 43. If the engine has come to rest in a position in which the cam 39 does not en- 25 gage the breaker arm 40, then the spring 45 will be in control of said arm, the vibrator circuit will be interrupted because 39 has broken connection with 40, and the single spark circuit will be closed through the 30 point 26, contact 29, point 27, the generator 9, and the primary 3 of the spark coil.

The mode of operation of this system is somewhat as follows: When it is desired to start the explosion engine, it is first necessary to place the ignition switch 31 into its position 47, when an attempt may be made to start the engine on compression by depressing the switch 46, thus closing the vibrator circuit independently of the cam 39. Should this fail to start the engine, then the operator may crank same, either by hand or mechanically, thus causing the cam 39 to revolve, as indicated in the figure. As soon as this cam strikes the circuit 45 breaker arm 40, the single spark circuit is interrupted at the points 42, 43, and the vibrator circuit is simultaneously energized. This circuit is, of course, closed at the points 21, 20, because as long as the engine is 50 standing still or is revolving very slowly, the spring 19 is in control of the automatic battery switch armature 17. As soon as the engine has "fired," its speed may be increased in a manner well understood, and, 55 when it reaches a value at which the generator "picks up," the interruption of the single spark circuit at the points 42, 43 will begin to produce single sparks, the magnitude of which will depend on the magni- 60 tude of the E. M. F. generated in the dynamo 9. At the same time, the shunt winding 15 of the automatic battery switch will also become energized. When the dynamo reaches a voltage which is approxi- 65 mately equal to the storage battery voltage,

the electromagnet 14 overpowers the spring 19, interrupts the vibrator circuit and connects the generator 9 to the battery 7 at the points 22, 23. But by this time, the interruption of the single spark circuit at 70 the points 42, 43 is producing single sparks of full intensity, for the voltage of the dynamo 9 has reached the same value as the voltage of the battery 7. When the generator is connected in parallel to the battery 75 through the battery switch, it not only supplies the energy for the single spark circuit, but also sends a charging current into the battery. Under these circumstances, no 80 vibrator sparks are produced. Should the engine speed fall below a certain value and reduce the voltage generated in the dynamo to a value below that of the battery 7, then the latter will send a discharging current into the generator. This discharging current, 85 circulating through the winding 16, will produce a magnetization opposed to that of the winding 15, will weaken the electromagnet, and will allow the spring 19 to resume control, thus reëstablishing the production of vibrator sparks. These vibrator 90 sparks will be preceded by a more or less energetic single spark, as long as the generator 9 produces any voltage at all.

The condenser 44 is connected across the 95 single spark contacts 42, 43, and the condenser 38 is connected across the vibrator contacts 36, 37, in order to minimize sparking at said contacts and increase the efficiency of the spark coil. The fuse 50 is inserted in the 100 single spark circuit for the purpose of protecting the same in case the automatic battery switch fails to connect the generator to the battery after the former has reached the proper voltage. Should the automatic 105 switch fail to perform this duty, then the voltage of the generator will increase far beyond its normal value and may, thereby, damage the spark coil. The fuse 50 will prevent such an accident. It will be seen 110 that the cam 39 contacting with the circuit breaker arm 40, performs the duty of a timer for the vibrator circuit. It is obvious that the functions of cam and timer need not be combined. If it is preferred not to 115 do so, then the stationary contact 37 of the vibrator should be connected to point 41 of the primary ignition circuit through a timer of ordinary construction, when the cam 39 may be grounded in the usual manner and 120 caused to strike an insulated portion of the circuit breaker arm, say a fiber block located 125 therein.

Having fully described my invention, what I claim as new and desire to secure by 125 Letters-Patent of the United States is:

1. In an ignition system for internal combustion engines, a secondary ignition circuit, an exciting coil for energizing said secondary circuit, means comprising coöperating 130

- contacts for making and breaking the circuit through the exciting coil, other means for making and breaking the circuit through the exciting coil comprising a vibratile element, 5 and means connecting said last named circuit interrupting means in circuit with the exciting coil approximately coincident with the separation of the contacts of the first mentioned circuit interrupting means.
- 10 2. In an ignition system for internal combustion engines, a secondary ignition circuit, an exciting coil for energizing said secondary circuit, a mechanically operated circuit breaker for the exciting coil, a vibratile circuit breaker, and means for connecting the vibratile circuit breaker in circuit with the exciting coil at the time the contacts of the mechanical circuit breaker are separated.
- 15 3. In an ignition system for internal combustion engines, a secondary ignition circuit, an exciting coil for energizing said secondary circuit, a battery, a dynamo electric machine, two circuit breakers for the exciting coil, and means adapted to render one circuit breaker inoperative and to connect the dynamo in circuit with the battery.
- 20 4. In an ignition system for internal combustion engines, a secondary ignition circuit, an exciting coil for energizing said secondary circuit, a battery, a dynamo electric machine, two circuit breakers, a switch adapted to disconnect one circuit breaker from the exciting coil and to connect the dynamo in circuit with the battery, and 25 means governed by the voltage of the dynamo for operating said switch.
- 25 5. In an ignition system for internal combustion engines, a secondary ignition circuit, an exciting coil for energizing said secondary circuit, a circuit breaker for the exciting coil comprising coöperating contacts, a vibratile circuit breaker, and a cam actuated by the engine and adapted to separate the contacts of the first mentioned circuit breaker and connect the vibratile circuit breaker in circuit with the exciting coil.
- 30 6. In an ignition system for internal combustion engines, a secondary ignition circuit, an exciting coil for energizing said secondary circuit, a circuit breaker for the exciting coil comprising coöperating contacts, a vibratile circuit breaker, and a cam actuated by the engine and adapted to simultaneously 35 separate the contacts of the first mentioned circuit breaker and connect the vibratile circuit breaker in circuit with the exciting coil.
- 35 7. In an ignition system for internal combustion engines, a secondary ignition circuit, an exciting coil for energizing said secondary circuit, a mechanically operated circuit breaker for the exciting coil, a vibratile circuit breaker, means for connecting the vibratile circuit breaker in circuit with the exciting coil, and a dynamo driven by the engine and permanently connected in series with the exciting coil through the mechanically operated circuit breaker.
- 40 8. In an ignition system for combustion engines, a secondary ignition circuit, an exciting coil for energizing said secondary circuit, a battery, a mechanically operated circuit breaker and a vibratile circuit breaker for the exciting coil, a dynamo connected in series with the exciting coil through the mechanically operated circuit breaker, and means for connecting the battery in circuit with the exciting coil through the vibratile circuit breaker, said means comprising a switch adapted to disconnect the battery from the vibratile circuit breaker and to connect the battery in circuit with the dynamo.
- 45 9. In an ignition system for combustion engines, a secondary ignition circuit, an exciting coil for energizing said secondary circuit, a battery, a mechanically operated circuit breaker and a vibratile circuit breaker for the exciting coil, a dynamo connected in series with the exciting coil through the mechanically operated circuit breaker, means for connecting the battery in circuit with the exciting coil through the vibratile circuit breaker, said means comprising a switch adapted to disconnect the battery from the vibratile circuit breaker and to connect the battery in circuit with the dynamo, and means governed by the voltage of the dynamo for operating said switch.

In testimony whereof, I have hereunto set my hand and affixed my seal in the presence of the two subscribing witnesses.
